UNITED STATES PATENT OFFICE

2,153,048

GOVERNOR

William E. Leibing, Detroit, Mich., assignor to
 Leibing Automotive Devices, Inc., Detroit,
 Mich., a corporation of Nevada

Application May 29, 1936, Serial No. 82,655

7 Claims. (Cl. 123—98)

This invention relates to methods and apparatus for governing the rate of fluid flow through a conduit, and more particularly to methods and apparatus for use in association with the intake manifold of an internal combustion engine for the purpose of automatically preventing the latter from operating above a predetermined maximum speed. The present invention constitutes an improvement over the methods and apparatus disclosed in copending application S. N. 738,114, filed August 2, 1934, of which I am a joint inventor, and my application S. N. 67,358, filed March 5, 1936.

In overcoming the disadvantages of the prior art, it is a major object of my invention to provide a governor for controlling fluid flow through a conduit in combination with novel means for preventing so-called throttle cheat, the factors entering into the actuation of the throttle cheat device being determined by fluid conditions within the conduit.

A further object of my invention is to provide novel means for preventing throttle cheat in combination with a governor located in the intake of an internal combustion engine wherein a pressure responsive element is provided to actuate said means, the fluid passing through the filter leading to the carburetor and entering into the intake manifold being utilized as the actuating force for the pressure responsive means.

A further object of my invention is to provide novel means for preventing throttle cheat in connection with a governor mounted in the intake of an internal combustion engine wherein a pressure responsive element is provided in connection with a throttle cheat preventer, the element being subject only to fluid that has been cleaned by the filter associated with the carburetor of the engine.

Still a further object of my invention is to provide a novel governor embodying means for preventing throttle cheat, the governor being tamper-proof and not subject to meddling by an unauthorized person.

A further object of my invention is to provide novel means for preventing throttle cheat in combination with a governor employed in an internal combustion engine wherein the need for a filter on the throttle cheat device is eliminated, and the cost of the complete assembly correspondingly reduced.

A further object of my invention is to provide a governor for use in connection with an internal combustion engine wherein novel means for preventing throttle cheat are employed includ-

ing a pressure responsive element, the latter being arranged so that atmospheric air cannot leak into the governor and interfere with the proper carburetion of the fuel mixture passing to the engine.

A further object of my invention is to provide a governor for use in connection with an internal combustion engine wherein novel means for preventing throttle cheat is employed including a pressure responsive element, the element being arranged in connection with the carburetor of the internal combustion engine so that it is subject only to air passing through the carburetor and subsequently into the intake manifold of the engine, and does not interfere with the supply of fuel to the engine nor disturb the quality of the fuel mixture.

A further object of my invention is to provide a governor for controlling fluid flow through a conduit in combination with novel means for preventing so-called throttle cheat, the latter means being relatively inexpensive and simple to manufacture as compared to the prior art devices.

Additional objects, many of a subordinate or more specific nature, will appear from a study of the following detailed description and the claims appended hereto when taken in connection with the accompanying drawing wherein:

Figure 1 is a diagrammatic view of the intake manifold of an internal combustion engine shown in connection with the carburetor and illustrating a preferred embodiment of the present invention.

Figure 2 is a section of the governor and a fragment of the intake manifold of Figure 1 shown in combination with a portion of the carburetor in section including the throttle thereof.

Figure 3 is a bottom plan view of the governor of Figure 2 with a portion of the throttle cheat device broken away to illustrate the structure of a preferred form of pressure responsive means for operating the governor.

Figure 4 is a view of a portion of the governor as viewed from the right of Figure 2 with the connections to the pressure-responsive mechanism shown in dotted lines.

With continued reference to the drawing, wherein like reference characters are employed to designate like parts, reference numeral 11 designates an apertured flange in a conduit 12 of a carburetor 13 to which air is supplied from an air filter 14 through a connection 15. Flange 11 is designed for attachment to a flange 16 of an intake manifold 17, but is shown separated

therefrom to provide a space for the reception of a governor generally indicated at G. If desired, a degassing device (not shown) may also be inserted between the manifold section and conduit 12 as described in connection with application S. N. 568,844, filed October 14, 1931.

Governor G has a cylindrical bore 18 formed therein aligned with carburetor conduit 12 and manifold passageway 17, bore 18 being formed 10 within a block 19. Block 19 is generally similar in shape and cross-section to flanges 11 and 16 of the carburetor and intake manifold, respectively, and cooperates therewith to form bores 21 for the reception of assembly bolts (not 15 shown) which serve to rigidly secure the governor in any desired position.

If desired, the bores 21 may be made slightly larger than the corresponding bores in the adjacent flanges so as to provide for ready connection of the governor to flanges of varying size. Suitable gaskets may be provided between the 20 contacting flanges to insure against leakage from the conduit.

It will be noted that substantially all mechanism associated therewith as will be hereinafter 25 described, is contained within planes passing through the flanges on governor block 19.

For a purpose that will be later described, one end of a bore 21 is enlarged as shown at 22 to 30 receive a bushing 23. Bushing 23 has an enlarged flange 24 thereon of a size to fit within a still larger aperture 25 formed in the block 19 concentric with bore 21. As will be noted from Figure 2, the aperture 25 is deeper than the 35 width of flange 24 on bushing 23 and defines an annular passage around the bushing for a purpose that will later appear.

Conduit 12 connected to the carburetor 13 contains a throttle valve 26, preferably of the butterfly type, which is arranged to be manually 40 operated to control the quantity of fuel mixture drawn into the intake manifold 17.

The governing device comprises an oscillatable valve mechanism 27 for throttling passageway 18 when the engine reaches a predetermined speed. Valve mechanism 27 comprises a fixed bridge member 28 and spaced vanes 29 and 31 arranged to pivot about an axis 32. Vane 31 is provided with a projection or lug 33 thereon which is arranged to cooperate with the throttle 50 cheat mechanism as will be later described.

The valve mechanism disclosed, together with the spring means which is employed to react against the effect of the fluid flowing through the conduit upon the vanes of the governor, is 55 fully described in my copending application S. N. 738,114, filed August 2, 1934, which issued May 25, 1937 as United States Patent No. 2,081,825, and a detailed consideration thereof in the present application is considered unnecessary.

In the present invention a relatively small bore or feed line 34 is formed in block 19, a plunger 35 being provided to reciprocate in bore 34 to contact lug 33 on vane 31 of the governor 27. 60 Plunger 35 is of a length to extend through a casing 36 formed upon the governor block 19 which contains a cylinder 37 within which operates a piston 38. Piston 38 is preferably cup-shaped as shown with the end of plunger 35 arranged to abut against the interior of the cup. A spring 39 is arranged to react against the wall 41 of cylinder 37 and against a pin 42 secured in a suitable aperture in the end of plunger 35 to normally maintain piston 38 in the right end 75 of cylinder 37. Piston 38 is preferably grooved

as shown at 43 to keep the leakage thereby to a minimum.

As shown in Figures 2 and 3, the end of cylinder 37 is open to facilitate manufacture thereof and assembly of the respective parts. After assembly, cylinder 37 is closed preferably by a suitable drive plug 44 to seal the piston against the access of atmosphere and to prevent tampering therewith. If desired, the drive plug 44 may be sealed by means of a suitable soft metal in 10 which an impression may be made, any unauthorized tampering with the plug being indicated by the mutilation of the impression.

A bore 45, preferably parallel to the axis of cylinder 37 is formed in block 19 extending from 15 a point adjacent the outer end of cylinder 37 to a passage or bore 47. A cross bore 46 leading from bore 45 to the interior of cylinder 37 at its end adjacent the drive plug 44 is provided as shown in Figure 4.

Bore 47 is arranged to connect with a bore 48 formed in the wall of the carburetor casing extending downwardly to an intersection with a bore 49 in the carburetor casing, the outer end of which is closed by a suitable plug 51. Bore 25 49 opens within the conduit 12 preferably at a point adjacent the upper end of the venturi 52 of the carburetor. This location of the bore 49 is desirable since by the location thereof adjacent the outer edge of venturi 52, the fluid entering 30 the bore 49 consists almost entirely of air since the fuel in the carburetor is discharged into the center of the venturi and at the point where the venturi meets the bore 49, only a negligible amount of fuel is found. This arrangement is 35 also advantageous in that there is no interference with the mixture passing to the intake manifold and no cutting off of the fuel supply or side-tracking thereof which might introduce irregularities in the feed of the proper fuel mixture to the engine.

As is evident from Figure 2, the piston 38 will be actuated when there is a difference in pressure between the conduit 18 adjacent the governor valve and the opening of the bore 34 into 4 bore 18, and the carburetor conduit adjacent the bore 49. When the differential of pressure is such that the pressure adjacent the bore 49 is greater than that adjacent the bore 34, piston 38 will move to the left against the action of the 5 spring 39, the plunger 35 contacting the lug 33 to move the governor to closed position. When a differential of pressure no longer exists or is materially reduced, spring 37 will force the piston and plunger back into the position shown in Figure 2 wherein the plunger has no effect upon the operation of the governor, and the throttle cheat device as a whole is inoperative.

It will be noted that this construction is such that the fluid employed in actuating the piston of the throttle cheat device is cleaned by the air filter attached to the carburetor. Moreover it will be noted that there is no aperture accessible to a dishonest driver or other unauthorized person to manipulate the governor, nor is there any possibility of leakage of the fuel mixture in passing through the engine.

If desired, a bore 53 may be provided leading from the cylinder 37 to the interior of conduit 18 to further facilitate the transmission of pressure from the conduit 18 to the cupped end of the piston 36.

To prevent repeated contact between piston 38 and the drive plug 44, a pin 54 may be secured

across cylinder 37 adjacent the drive plug 44 to receive the impact of the piston.

From the foregoing disclosure it will be seen that I have provided a device whereby it is impossible by improper manipulation of the throttle valve to gradually build up a fuel supply without disturbing the position of the governor valve, and obtain speeds far in excess of those at which the governor is set to operate, or in other words 10 throttle-cheat the governor.

Moreover, my improved structure insures against dilution of the fuel mixture passing into the intake manifold of the engine, insures operation of the throttle cheat device when such 15 operation is desired, and provides a supply of clean air to the engine.

It is also apparent upon comparing the present invention with the device of my Patent No. 2,081,825 and prior art devices that the necessary screening and securing nut together with the operation of tapping the cylinder and threading the governor block are all eliminated and replaced by drilled holes and a drive plug which does not permit of tampering.

25 While in the present embodiment of the invention I have shown a butterfly valve employed in connection with the governor, it is to be understood that other types of throttle valves may be employed and the parts of the governor suitably modified so that such throttle valves may be used to control the pressures effective when the pressure responsive element is operating the governor valve.

The invention may be embodied in other specific forms without departing from the spirit or essential characteristics thereof. The present embodiment is therefore to be considered in all respects as illustrative and not restrictive, the scope of the invention being indicated by the 40 appended claims rather than by the foregoing description, and all changes which come within the meaning and range of equivalency of the claims are therefore intended to be embraced therein.

45 What is claimed and desired to be secured by United States Letters Patent is:

1. In combination with a carburetor for an internal combustion engine, said carburetor forming a part of the fuel intake conduit for said engine 50 and having a conduit and a throttle valve associated therewith, a governor valve in said conduit for governing the flow of fuel mixture to said engine from said carburetor and responsive to the rate of flow of fuel mixture, pressure responsive means to operate said governor valve, means to subject said pressure responsive means to the pressure of said fuel mixture adjacent said governor valve, and means to subject said pressure responsive means to the pressure of said fuel mixture between said throttle valve and the point in said carburetor where said fuel mixture is made.

2. In combination with a carburetor for an internal combustion engine, said carburetor forming a part of the fuel intake conduit for said engine and having a conduit, a throttle and an air filter associated therewith, a governor valve in said conduit for governing the flow of fuel mixture to said engine from said carburetor and responsive to the rate of flow of fuel mixture, pressure responsive means to operate said governor valve and means to subject said pressure responsive means to a differential of pressures in

the fuel mixture adjacent said governor valve and between said throttle and said air filter.

3. In combination with a carburetor for an internal combustion engine, said carburetor having a venturi therein, a governor for governing the flow of fluid to said engine from said carburetor, pressure responsive means to operate said governor, and means to subject said pressure responsive means to a differential of pressures in the fluid adjacent said governor and the fluid adjacent the 10 downstream end of said venturi.

4. In combination with a carburetor for an internal combustion engine, said carburetor having a venturi therein, a passage through which fluid flows from said carburetor to said engine, a governor for governing the flow of fluid from said carburetor to said engine disposed in said passage, pressure responsive means to operate said governor, a conduit to connect one side of said pressure responsive means to the fluid passage 20 adjacent said governor, and a second conduit to connect the opposite side of said pressure responsive means to said carburetor at a point adjacent the downstream end of said venturi.

5. In combination with a carburetor for an internal combustion engine, said carburetor having an air filter associated therewith, a throttle valve in said carburetor, a governor for governing the flow of fuel mixture therethrough for governing the flow of fuel mixture from said carburetor to 30 said engine to limit said engine to a predetermined speed, and pressure responsive means to operate said governor, said pressure responsive means being subject to the differential between the pressure of the fuel mixture adjacent said 35 governor and the pressure of the fluid between said throttle valve and the filter.

6. In combination with a carburetor for an internal combustion engine, said carburetor forming part of the fuel intake conduit for said engine 40 and having a conduit and an air filter associated therewith, a governor valve in said conduit for governing the flow of fuel mixture to said engine from said carburetor and responsive to the rate of flow of fuel mixture, means to oppose closing 45 movement of said governor valve in response to the rate of fuel flow to govern said engine at a predetermined speed, pressure responsive means to operate said governor valve, means to subject said pressure responsive means to the pressure of fuel mixture adjacent said governor, and means to subject said pressure responsive means to the 50 pressure of fluid which has passed through said carburetor filter.

7. In combination with a carburetor for an internal combustion engine, said carburetor forming part of the fuel intake conduit for said engine, a throttle therein, a governor valve in said conduit for governing the flow of fuel mixture to said engine from said carburetor and responsive to the rate of flow of fuel mixture, means to oppose closing movement of said governor valve in response to the rate of fuel flow to govern said engine at a predetermined speed, pressure responsive means to operate said governor valve, a conduit to subject one side of said pressure responsive means to the pressure of fuel mixture adjacent 60 said governor valve and a second conduit to subject the opposite side of said pressure responsive means to the pressure in said carburetor at a 65 point upstream of said throttle.
